UNITED STATES PATENT OFFICE.

FREDERICK B. TOWNSEND, OF CHICAGO, ILLINOIS, ASSIGNOR TO WILLIAM H. MINER,
OF CHAZY, NEW YORK.

HAND BRAKE FOR RAILWAY CARS.

Application filed September 5, 1919. Serial No. 321,757.

To all whom it may concern:

Be it known that I, FREDERICK B. TOWNSEND, a citizen of United States, residing at Chicago, in the county of Cook and State 5 of Illinois, have invented a certain new and useful Improvement in Hand Brakes for Railway Cars, of which the following is a full, clear, concise, and exact description, reference being had to the accompanying 10 drawings, forming a part of this specification.

This invention relates to improvements in hand brakes for railway cars.

The object of the invention is to provide 15 an efficient hand brake especially adapted for flat cars or logging cars wherein the operating members must be confined within pre-determined relatively narrow limits in order to clear the lading, which brake will be easy 20 to operate and with safety to the brakeman.

In the drawing forming a part of this specification, Figure 1 is a partial top plan view of a flat car showing my improvements in connection therewith. Fig. 2 is a side 25 elevation of the construction illustrated in Fig. 1. Fig. 3 is a horizontal sectional view taken substantially on the line 3—3 of Fig. 4. Fig. 4 is a vertical sectional view taken substantially on the line 4—4 of Fig. 3. Fig. 5 is an end elevational view of the 30 structure illustrated in Figs. 1 and 2. And Fig. 6 is a detailed sectional view taken substantially on the line 6—6 of Fig. 4.

In said drawing, 10 denotes the flooring 35 of a flat or logging car, 11 the end sill and 12 one of the side sills. Said car is provided with the usual end grab irons 13, side step 14, side grab iron 15 and top grab iron 16.

The improved brake, as shown, comprises, 40 broadly, a vertical chain winding or brake staff, A, a housing or casing B, a ratchet wheel C, an operating lever or handle D, a pawl E, a locking dog F, a spring G, a plate H, and a release lever K.

The housing B is of generally cylindrical 45 form and has a detachable or separable bottom wall 17 to permit assembling of the parts and said housing is further provided with a bottom flange 18 by which the same 50 may be bolted or secured to the end sill of the car.

The staff A extends vertically and is suitably journaled at its lower end and may be provided with the usual chain winding drum 55 or hub. At its upper end, the staff A is

provided with a squared or other non-circular section 19 disposed within the housing B.

The ratchet wheel C is provided with a vertically extended hollow hub 20 adapted to fit the non-circular section 19 of the staff so as to be rotatable in unison therewith. Said hub 20, however, is made long enough so that there is normally a space or clearance 21 between the upper wall of said hub and the top of the staff A. The ratchet wheel C is held in its uppermost position by the spring G acting through the plate H but it will be evident that said ratchet wheel C may be depressed or slid vertically with respect to the staff A against the action of the spring. 60

The operating handle or lever D moves in a horizontal plane as indicated by the arrows in Fig. 1. Said lever is provided at its inner end with an annular sleeve 22 adapted to fit the hub 20 and thereby provide for the oscillation of the lever. Said lever is also provided with oppositely extended arcuate flanges 23—23 which are arranged to cover the slot 24 in the housing B in which the lever D moves and thereby prevent dirt or other foreign matter getting within the housing. The pawl E is of the gravity type and is pivotally supported on a pin or bolt 25 carried by the lever D, said pawl cooperating with the radially arranged ratchet teeth 26 in the upper face of the ratchet wheel C. 70

To hold the ratchet wheel and staff A against reverse rotation, the locking dog F is provided which is also of the gravity type and mounted on a pin or bolt 27 supported in 75 the outer wall of the housing B and the transverse flanges 28. The ratchet wheel C is normally held in its uppermost position by the spring G as heretofore explained. To

release the brake, the lever K is elevated 80 about its pivot 29 so that the inner end thereof engages and depresses the hub 20 of the ratchet wheel. This of course forces the ratchet wheel downwardly and ultimately 85 will disengage the ratchet teeth 26 from the pawl E and dog F. To insure this operation, the dog and pawl are each provided with a shoulder as indicated at 30 in Fig. 6 which is adapted to engage with an adjacent flange or wall 31 of the housing so as to limit 90 the downward movement of the pawl or dog as clearly illustrated in Fig. 6. In actual 95 practice, I would so design the said shoulders 30 that the pawl will be held or restrained prior to the dog so that, as the ratchet wheel 100

105

110

C is depressed, it will first become disengaged from the pawl and subsequently from the locking dog. By this arrangement, the danger of having the operating lever suddenly swung around during the release is avoided and the operating lever will be positively free from the ratchet wheel by the time the latter is released from the locking dog.

10 As will be evident from an inspection of the drawings taken in connection with the preceding description, the brakeman can easily operate the lever D while standing on the step 14. The arrangement is such that 15 several inches clearance are provided for the brakeman's hand between the lever and the floor of the car and also between the lever and the under side of the load which will be spaced approximately eight inches 20 above the floor level at the end of the car. The release lever is so positioned that it can be conveniently grasped by the brakeman and all parts are so located that they do not project beyond the outlines of the car.

25 I claim:

1. In a brake of the character described, the combination with a vertically disposed rotatable element for effecting winding of a flexible member, of a housing adapted to 30 be secured to a horizontally extending member, a single faced ratchet wheel within the housing, rotatable in unison with said element, a horizontally swinging operating lever having one end movable about said 35 element, a pawl carried between the ends of said lever cooperable with said ratchet wheel, a locking dog cooperable with said ratchet wheel, and means including a second lever, for effecting relative separation of 40 the ratchet wheel on the one hand and the pawl and dog on the other hand to thereby release said element, said pawl and dog both being located on the same side of said ratchet wheel.

45 2. In a brake of the character described, the combination with a vertically disposed rotatable element for effecting winding of a flexible member, of a housing adapted to 50 be secured to a horizontally extending member, a ratchet wheel within the housing rotatable in unison with said element and vertically movable with respect thereto, an operating lever, a pawl pivotally carried by 55 said lever and cooperable with said ratchet wheel, a pivotally mounted locking dog cooperable with said ratchet wheel, means normally retaining said ratchet wheel, pawl and dog in cooperative relation, and means for effecting relative separation of the

ratchet wheel and pawl and dog to release 60 said element.

3. In a hand brake of the character described, the combination with a vertical rotatable brake staff, of a housing, a ratchet wheel disposed within said housing and rotatable in unison with said staff, an operating lever oscillatable in a horizontal plane, a gravity pawl carried thereby cooperable with said ratchet wheel, a gravity locking dog cooperable with said ratchet wheel both 70 the pawl and dog being located on the upper side of said ratchet, a spring normally supporting said ratchet wheel in operative position, and means for depressing said ratchet wheel to thereby disengage it from 75 said pawl and dog.

4. In a brake for flat cars and the like, the combination with a vertical brake staff, a housing adapted to be secured on top of the car, a ratchet wheel disposed within said 80 housing and rotatable in unison with said staff, a spring acting against said ratchet wheel to normally hold it in operative position, an operating handle oscillatably mounted on said ratchet wheel and extending 85 to the exterior of the housing, a pawl pivotally mounted on the handle cooperable with said ratchet wheel, a locking dog mounted within the housing also cooperable with said ratchet wheel, and a release lever 90 independent of said operating handle pivotally mounted on said housing and adapted to depress said ratchet wheel against the action of said spring and thereby disengage 95 the ratchet wheel from the pawl and dog.

5. In a brake of the character described, the combination with a vertically disposed rotatable element for effecting winding of a flexible member, of a housing adapted to 100 be secured to a horizontally extending member, a single face ratchet wheel within the housing rotatable in unison with said element, said ratchet wheel having a single 105 set of teeth, an operating lever, a pawl carried thereby cooperable with said set of teeth, a locking dog cooperable with said set of ratchet teeth and means including 110 a second lever for effecting relative separation of the ratchet wheel on the one hand and the pawl and dog on the other hand to thereby release said element, said pawl and dog both being located on the same side of 115 said ratchet wheel.

In witness that I claim the foregoing I have hereunto subscribed my name this 1st day of Sept., 1919.

FREDERICK B. TOWNSEND.
